DISPLAY STAND ATTACHMENT

Ralph N. Richards, Toledo, Ohio, assignor to
Ottawa River Paper Company, Toledo, Ohio, a
corporation of Ohio

Application January 16, 1932. Serial No. 587,101

7 Claims. (Cl. 211—156)

This invention relates to a display stand attachment which is adapted to be made of corrugated paper, strawboard or similar sheet material and to be used in connection with a combination shipping case and display stand of the type shown and described in my earlier application, Serial No. 580,270, filed December 11, 1931, and issued February 7, 1933, as Patent No. 1,896,721.

10 The general object of the invention is to provide an attachment or accessory which may be packed and shipped flat within the combined shipping case and display stand of the character referred to and which, when set up within 15 the opened end of the shipping case, forms a series of successive steps or shelves on which articles may be supported and displayed most effectively.

The invention will be more particularly described in connection with the accompanying drawing, in which—

20 Figure 1 is a perspective view of a shipping case in connection with which the invention may be used;

25 Figure 2 is a perspective view of the shipping case with the top cut off;

Figure 3 is a perspective view of the same case folded to receive the attachment which constitutes the support on which the goods are to be 30 displayed;

Figure 4 is a perspective view of the attachment or insert folded flat for shipment;

Figure 5 is a rear perspective view of the insert or attachment set up;

35 Figure 6 is a perspective view of the display stand with the insert in place;

Figure 7 is a front perspective view of the insert; and

40 Figure 8 is a similar view showing the use of additional inserts for providing additional shelves.

The combined shipping case and stand in connection with which my invention is used is formed from a single blank folded to form the four sides 10, 11, 12 and 13, the meeting edges of the blank being usually bound together by cambric tape or other suitable material, as indicated at 15, to meet railroad classifications for shipping containers. The blank is also provided with end flaps 16 which are folded to form the ends of the box.

When a shipment has been received in this shipping case, in order to form a display stand, the top 21 should be carefully cut away, as indicated in Fig. 2, the line for cutting, together with

directions, being printed on the outside of the container, if desired.

In order that the shipping case may be especially adapted to be converted into a floor display stand, fold lines 23, 24 and 25 are scored on the inside of the panels 11, 12 and 13 respectively, before the blank is folded to form the case. In order to facilitate the conversion, the panel 12 is also provided with diagonal score lines 26 extending from the ends of the fold line 24 to the upper end of the panel 12 midway between the sides thereof. After the top 21 has been removed and the contents of the case taken out, the upper portion of the panel 12 may be folded inwardly across the case, as shown at 27 in Fig. 3, to form a horizontal seat for receiving the insert which supports the goods for display. The upper part of the rear panel 10 then serves as a back for the seat, as indicated at 28, while the sides are doubled about the lines 23 and 25 to a triangular shape as shown at 29 and 30.

The attachment or insert, to which the present invention relates, may be folded flat as shown in Fig. 4 and shipped within the case illustrated in Fig. 1. This insert is made from a single rectangular sheet which is creased on the lines 31 and 32 and the end panels folded back to form two plies, the meeting ends of the panels being bound together by tape 33 of cambric or other suitable material, which constitutes a hinge 35 member connecting the two panels. The insert is also creased transversely as indicated by the lines 34, 35 and 36, so that when the insert is set up, as shown in Figs. 5, 6 and 7, it forms steps or shelves 37 and 38 and risers 39 and 40. The insert is of such width that it fits rather tightly between the sides of the shipping case and it is desirable, though not necessary, to bind the edges of the two plies together adjacent the fold lines 34 and 25 with tape as indicated at 41.

It is possible to provide additional steps and risers by providing additional inserts 42 and 43, as shown in Fig. 8. Each of these additional inserts is made in the same manner as the insert shown in Fig. 7, but the blank from which it is made is only half as long and its steps and risers are only half as wide as those of the first insert.

After the shipping case has been prepared as shown in Fig. 3, the insert may be set up merely by taking hold of its two ends and folding it so that the two panels of the rear ply are substantially at right angles to each other as shown in Fig. 5. The creases 34, 35 and 36 are so formed that the insert tends to resume its flat shape; but after it has been inserted in the seat provided for

it in the shipping case, it is held in position not only by its engagement with the sides 29 and 30 but by the weight of the goods as they are supported on the steps or shelves 37 and 38. The additional inserts 42 and 43 will be held in position in the same manner. Thus the shipping case may be very quickly and easily converted into a display stand on which goods may be most effectively displayed.

10 While I have shown and described the invention specifically in its preferred form, it is understood that it is not limited thereby but includes all such modifications as may fall within the scope of the appended claims.

15 What is claimed is:

1. In a display stand formed with a seat having upright back and sides, an insert therefor comprising a sheet folded double and fitting between said sides, the rear ply of said insert including panels for facing said seat and back respectively, the front ply thereof being creased to form two steps and two risers when the insert is set up, and an additional insert for each step of the first insert, each additional insert being similar in construction to the first insert except that its steps and risers are approximately half as wide.

2. In a display stand formed with a seat having upright back and sides, an insert therefor comprising a sheet folded double and fitting between said sides, the ends of said sheet meeting substantially midway of the rear ply of the insert, and a hinge member joining said ends, thus constituting two hingedly connected panels for facing said seat and back respectively, the front ply of the insert being creased to form two steps and two risers when the insert is set in position, and an additional insert for each step of the first insert, each additional insert being similar in construction to the first insert except that its steps and risers are approximately half as wide.

3. In a display stand formed with a seat having upright back and sides, an insert therefor comprising a sheet folded double and fitting between said sides, the ends of said sheet meeting substantially midway of the rear ply of the insert, and a hinge member joining said ends, thus constituting two hingedly connected panels for facing said seat and back respectively, the front ply of the insert being creased to form two steps and two risers when the insert is set in position, the edges of the lower step and of the upper riser being bound to the corresponding edges of

the rear panel, and an additional insert for each step of the first insert, each additional insert being similar in construction to the first insert except that its steps and risers are approximately half as wide.

4. An insert for the purpose described, comprising a sheet with end panels folded rearwardly and meeting, each of said end panels being substantially equal in area to one-fourth of the sheet, a hinge member joining the meeting ends, the front ply of the sheet thus folded being creased transversely in such a manner as to form two steps and two risers when said end panels are disposed substantially at right angles to each other, the edges of the upper riser and of the lower step being closely bound to the corresponding edges of said end panels.

5. In a display stand formed with a seat having upright back and sides, an insert therefor comprising a single sheet with upper and lower end panels folded rearwardly to constitute facings for the back and seat of the stand respectively, the front portion of the sheet being creased to define two steps and two risers when the insert is set up, the side edges of the lower step and the upper riser being bound to the corresponding edges of the rearwardly folded panels.

6. In a display stand formed with a seat having upright back and sides, an insert therefor comprising a single sheet with upper and lower end panels folded rearwardly to constitute facings for the back and seat of the stand respectively, the combined area of said panels being substantially one-half of the total area of the sheet, the front half of the sheet being creased to define two steps and two risers when the insert is set up, the side edges of the lower step and the upper riser being bound to the corresponding edges of the rearwardly folded panels.

7. In a display stand formed with a seat having upright back and sides, an insert therefor comprising a single sheet with upper and lower end panels folded rearwardly and meeting to constitute facings for the back and seat of the stand respectively, and a hinge connection between the meeting edges of the panels, the front portion of the sheet being creased to define two steps and two risers when the insert is set up, the side edges of the lower step and the upper riser being bound to the corresponding edges of the rearwardly folded panels.
